US00D893711S

(12) **United States Design Patent** (10) **Patent No.:** **US D893,711 S**
(45) **Date of Patent:** **** Aug. 18, 2020**

(54) **CATHETER ASSEMBLY**

(71) Applicant: **Smiths Medical ASD, Inc.**, Plymouth, MN (US)

(72) Inventors: **Harsh D. Chheda**, Cheshire, CT (US); **Kathryn Felicito**, Cheshire, CT (US); **Christopher Roehl**, New Hartford, CT (US)

(73) Assignee: **Smiths Medical ASD, Inc.**, Plymouth, MN (US)

(**) Term: **15 Years**

(21) Appl. No.: **29/627,967**

(22) Filed: **Nov. 30, 2017**

Related U.S. Application Data

(62) Division of application No. 29/582,452, filed on Oct. 27, 2016, now Pat. No. Des. 808,013.

(51) **LOC (12) Cl.** **24-02**

(52) **U.S. Cl.** **USPC .....** **D24/130**

(58) **Field of Classification Search**

(57) **CLAIM**

We claim the ornamental design for a catheter assembly, substantially as shown and described.

DESCRIPTION

FIG. 1 is a top perspective view depicting a catheter assembly.

FIG. 2 is a top view thereof.

FIG. 3 is a bottom view thereof.

FIG. 4 is a right side view thereof.

FIG. 5 is a left side view thereof.

FIG. 6 is a rear view thereof; and,

FIG. 7 is a front view thereof.

The broken lines are depict environmental subject matter only and form no part of the claim.

1 Claim, 4 Drawing Sheets
